REMOVABLE SHIFT BINDER

Paul O. Unger, Glen Ellyn, Ill., assignor to Wilson-Jones Company, Chicago, Ill., a corporation of Massachusetts

Application October 21, 1932, Serial No. 638,849

12 Claims. (Cl. 129—17)

This invention relates to loose leaf binders having means to shift one or more sheets within a binder relatively to the rest of the sheets, without disturbing the relationship between the sheets being shifted. Although the invention is applicable to loose leaf binders of any kind, it is of particular advantage in connection with so-called visible index binders in which a plurality of relatively short sheets are arranged in vertically overlapping relationship so that a predetermined area on each sheet is exposed whenever the binder is opened.

In order to obtain the full benefits of loose leaf visible index binders it is essential that the sheets be maintained in some definite arrangement. When it is necessary to insert a new sheet between any two sheets in the binder, it is necessary to shift all the sheets on one side of the proposed insertion space up or down one space to maintain the visibility feature of the binder. Although shifting of this type, that is from one position to another within the same binder, is generally confined to visible index binders, it is quite often desirable to provide other types of binders with means to shift all or a portion of the sheets from one binder to a different binder.

It is an object of this invention to provide means for facilitating the insertion, removal and rearrangement of one or more sheets in a binder without disturbing the relative arrangement of the remainder of the sheets.

It is a further object of this invention to provide means for shifting one or more of a plurality of sheets impaled on posts or prongs in a binder either up or down with respect to the other sheets in the binder without removing any of the sheets from the posts.

It is a further object of this invention to provide a removable post supporting bar forming a part of the binder adapted to carry all or a portion of the sheets of the binder and to fit universally into any similar binder of the same size so that any desired number of sheets may be shifted from one binder to a different binder of the same kind without disturbing the relative arrangement of the sheets or removing the sheets from the posts or prongs upon which they are impaled in the binder.

It is a further object of this invention to provide means for shifting a portion of the contents of a loose leaf binder with respect to the rest of the contents so that the binder may be closed before the shifting operation is completed without any possibility of damaging either the shift mechanism or the sheets.

It is a further object of this invention to provide a loose leaf binder embodying a removable shift bar that is inexpensive to manufacture, simple and efficient in operation, and is capable of withstanding rough usage in service.

Other objects of this invention will become apparent upon reading the following description taken in conjunction with the accompanying drawings in which:

Figure 1 is a perspective view of a binder embodying the invention;

Figure 2 is a plan view of the binder with the cover members removed;

Figure 3 is a longitudinal section taken on the line III—III of Figure 2;

Figure 4 is a cross section taken on the line IV—IV of Figure 2, with parts broken away to facilitate the illustration;

Figure 5 is a perspective view of the removable post carrying bar;

Figure 6 is a cross section taken on the line VI—VI of Figure 3; and

Figure 7 is a cross section taken on the line VII—VII of Figure 2.

In the drawings the reference numeral 1 designates the back member of the binder which comprises two sections 2 and 3 hinged together at 4. Cover members 5 and 6 are hinged to the back sections 2 and 3 at 7 and 8, respectively. The back section 2 is provided with end members 9 and 10, and the back section 3 is provided with end members 11 and 12.

An arcuate plate 13 having a plurality of V-shaped notches 14 is riveted or welded to the inner face of each of the end members 9 and 10. A rod 15 is rotatably mounted on pins or trunnions 16 extending through the end members 11 and 12. A pawl 17 is fixed to the rod 15 adjacent each end thereof. One end of the pawl 17 is provided with a tooth 18 adapted to engage with the notches 14 in the plate 13 to hold the back sections 2 and 3 in any of several predetermined positions. The other end of the pawl 17 is provided with a finger piece 19 so that the tooth 18 may be readily disengaged from the notches 14.

A coiled spring 20 encircles each end of the rod 15 and has one end secured to a pin 21 projecting from the inner surface of the pawl 17. The other end of the spring 20 butts against the wall of the back section 3. The spring exerts constant pressure urging the tooth 18 into engagement with the notches 14 so that the back sections may be closed without manipulation of the pawl 17. The shape of the tooth 18 and

notches 14, however, prevent separation of the back sections 2 and 3 until the finger piece 19 is depressed to move the tooth 18 out of engagement with the notch 14. Since both pawls 17 are fixed to the rod 15, manipulation of either finger piece 19 is sufficient to move both pawls 17 to disengage the tooth 18 of each from its respective notch 14.

The plate 22 is of inverted U-shape and carries 10 a series of arcuate shaped sheet retaining posts or prongs 23. The base portions of the posts 23 are flattened, as indicated at 24, and are welded to the plate 22. The free ends of the posts 23 are pointed, as indicated at 25, to facilitate positioning 15 a plurality of sheets 26 thereon. As shown in Figure 1, the sheets 26 are considerably shorter than the binder and are arranged on the posts in overlapping relationship so that a definite predetermined area at the lower edge of each 20 sheet is exposed, and the major portion of each sheet is covered by the preceding sheet. Any desired indicia may be typed on the exposed surface of the sheets and constitute a visible index for the contents of the binder. Equalizer sheets of 25 any desired kind may be inserted between each bank of sheets to maintain a uniform level for the sheets.

Sheet retaining posts 27, similar to the posts 23 have their flattened base portions 28 welded to 30 a removable bar 29. The bar 29 is substantially of inverted U-shape, but has one edge bent back on itself, as indicated at 30, to form an abutment for a purpose hereinafter described. The longer wall of the bar 29 has portions cut away to form 35 two groups of recesses 31 which are adapted to cooperate with a pair of projections 32 secured to the inner face of the back section 2 to position the bar 29. The bar 29 is shown as having three recesses 31 in each group, although the number 40 might be varied at will.

The plate 22 and the bar 29 are each provided with a series of recesses 32' to receive the pointed ends of the posts carried by the other. The 45 number of recesses 32' between adjacent prongs is the same as the number of recesses 31 in each group, and the spacing is the same. Since the spacing of the recesses 31 determines the units of distance the bar 29 may be moved, the pointed ends of each post will always be received in a recess in the plate 22 or the bar 29 regardless of the particular position of the bar 29 when the back sections 2 and 3 are closed.

The bar 29 is maintained in place by a lock 55 bar 33 which includes an angular member 34 permanently secured to a flat member 35. The angular member 34 is provided with a flange 36 adapted to interlock with the bent over member 30 to prevent any possibility of accidental displacement of the bar 29. The lock bar 33 is pivoted at each end to a toggle link 37 as indicated 60 at 38. The opposite end of the toggle link 37 is pivoted at 39 to a bracket 40 rigidly secured to the back section 2.

One end of the flat portion 35 of the lock bar 65 33 extends through a slot 41 cut out of the end member 9. A finger piece 42 is secured to the end of the lock bar 33. The lock bar 33 is provided with a shallow recess 33' (Figure 2) to allow it to have sufficient transverse movement to release the flange 36 from its interlocking engagement with the abutment 30 without binding on the pivot pin 39. As shown in Figure 2, the toggle link 37 is positioned slightly off center when the bar 33 is in locking position. Although the toggle 70 connection is preferred, it will be obvious that the 75

movement of the lock bar 33 might readily be guided by a suitable cam slot cooperating with pins projecting from the brackets 40. In either case the frictional contact between the lock bar 33 and the removable bar 29 is generally sufficient to maintain the removable bar in position.

In order to increase the security with which the lock bar is held in position, a flat spring member 43 is welded or riveted to the plate 13. The member 43 is twisted to present a flat surface in contact with the flat portion 35 of the lock bar. The plate 13 adjacent the spring member 43 is cut away, as indicated at 44, Figure 4, to permit the flat portion of the spring to lie adjacent the inner surface of the end member 9. As shown in Figure 7, the spring member 43 is provided with a projection 45. The flat portion 35 of the lock bar 33 is provided with two recesses 46 and 47. The projection 45 springs into the recess 46 to maintain the lock bar 33 in locked position and 20 into the recess 47 to maintain it in unlocked position.

The operation of the binder may be summarized as follows, assuming that it is desired to insert a sheet 26 between the two sheets designated in Figure 1 as 48 and 49:

The sheet 48 and all preceding sheets are moved to the left side of the binder while the sheet 49 and all therebelow remain on the right side of the binder as shown in Figure 1. Either finger 30 piece 19 is then depressed to release the pawl teeth 18 from engagement with the notches 14 and the back sections 2 and 3 are separated to the limit of their motion. The sheet to be added may then be positioned on the sheet retaining posts 23 in the same position previously occupied by the sheet 48. The locking bar 33 is then moved to unlocking position, and the removable bar 29, with the sheet 48 and those preceding it, is removed from the back section 2 and reinserted in 40 position with the projection 32 engaging the recess 31 just below the recess in which it was originally engaged. The lock bar is then moved to locked position and the back sections 2 and 3 are closed.

Although the above noted steps are sufficient 45 to arrange all of the sheets in the desired relationship, the removable bar 29 should be brought back to its normal position. This may be done by transferring all the sheets to the right hand portion of the binder, separating the back sections 50 2 and 3, unlocking the lock bar 33, removing the bar 29 and repositioning it in its original position, locking the lock bar 33, and then closing the back sections 2 and 3. Because of the fact that the 55 number of recesses 32' correspond with the number of recesses 31 in one group, the binder may be closed regardless of the position of the removable bar 29 without any possibility of damage to the binder or posts.

In view of the fact that the post carrying bar 29 is entirely separate from the rest of the binder, it will be obvious that said bar may be shifted from one binder to another binder of the same type without the necessity of moving the sheets off the posts 27.

While I have described a preferred embodiment of my invention in detail, it will be understood that the description thereof is illustrative rather than restrictive, as many details may be modified or changed without departing from the spirit or scope of my invention. Accordingly, I do not desire to be restricted to the exact construction described except as limited by the appended claims.

I claim:

1. In a loose leaf binder, a back member provided with a projection, a removable post carrying bar having a plurality of recesses adapted to cooperate with said projection to position said bar in said binder, and a locking bar movable in a plane perpendicular to said post carrying bar to clamp said post carrying bar in position. 5
2. In a loose leaf binder, a back member, a projection on said back member, a removable post carrying bar, a plurality of recesses on said bar adapted to cooperate with said projection to position said bar, and a locking bar adapted to be moved in a plane perpendicular to said post carrying bar to clamp said post carrying bar in position in said binder. 10
3. In a loose leaf binder, a lock bar, a flange extending longitudinally on said lock bar, and a removable post carrying bar, one edge of said post carrying bar being provided with an abutment adapted to cooperate with said flange to maintain said post carrying bar in position in said binder. 15
4. In a loose leaf binder, a removable post carrying bar, and a longitudinally extending lock bar adapted to be moved in a plane perpendicular to the plane of said post carrying bar into frictional contact with said post carrying bar to maintain said post carrying bar in position in said binder. 20
5. In a loose leaf binder, a removable post carrying bar, a lock bar adapted to hold said post carrying bar in position in said binder, and a toggle link adapted to permit limited movement of said lock bar, said toggle link being so arranged that it is positioned slightly past center when said lock- 25 ing bar is in holding position.
6. In a visible index shift binder, a pair of back sections hinged together, means for retaining said back sections in closed relationship, means operable from either end of said binder for releasing 30 said retaining means to permit movement of said back sections to open relationship, a removable post carrying bar, and a locking bar mounted in one of said back sections with its longitudinal axis parallel to said post carrying bar and movable in a plane perpendicular to said post carrying bar to clamp said post carrying bar in position in said back section. 35
7. In a loose leaf binder, a removable post carry- 40
- ing bar, a locking bar adapted to hold said post carrying bar in position in said binder, and a toggle link having one end secured to said locking bar to control the path of movement of said locking bar. 5
8. In a loose leaf binder, a back section, a removable post carrying bar receivable on said back section, a locking bar adapted to hold said post carrying bar in position on said back section, and a toggle link having one end secured to said locking bar and having its other end secured to said back section. 10
9. In a loose leaf binder, a pair of back sections hingedly connected together, a plurality of sheet retaining posts secured to one back section, a post carrying bar removably secured to the other back section, said bar being shiftable relative to said first mentioned posts, and a locking bar having its longitudinal axis extending parallel to said post carrying bar, said locking bar being movable in a plane perpendicular to said post carrying bar 15 to clamp said post carrying bar in position. 20
10. A loose leaf binder including a back member, a series of posts extending from each longitudinal edge of said back member and cooperating to constitute the sheet retaining means for said binder, one of said series of posts being carried by a bar removably mounted on said back member, and a locking bar having its longitudinal axis extending parallel to said first mentioned bar, 25 said locking bar being movable in a plane perpendicular to said first mentioned bar to retain said first mentioned bar against said back member. 30
11. In a loose leaf binder, a back section, a removable post carrying bar receivable on said back section, and a locking bar secured to said back section and movable to engage said post carrying bar along substantially its entire length to clamp it against said back section. 35
12. In a loose leaf binder, a back member, a removable bar, a plurality of posts secured to said bar, means on said bar and said back member to selectively position said bar in a plurality of predetermined positions, and a locking bar movable in a plane perpendicular to said removable bar 40 and engageable therewith to retain said removable bar in any of said predetermined positions. 45

PAUL O. UNGER.
